UNITED STATES PATENT OFFICE.

KATSURO ISHIBASHI, OF CHICAGO, ILLINOIS, ASSIGNOR TO AMERICAN STEEL
FOUNDRIES, OF CHICAGO, ILLINOIS, A CORPORATION OF NEW JERSEY.

SIX-WHEEL-TRUCK EQUALIZING ARRANGEMENT.

Application filed May 24, 1922. Serial No. 563,258.

To all whom it may concern:

Be it known that I, KATSURO ISHIBASHI, a subject of the Emperor of Japan, residing at Chicago, in the county of Cook and State 5 of Illinois, have invented certain new and useful Improvements in Six-Wheel-Truck Equalizing Arrangements, of which the following is a specification.

This invention relates to a six-wheel truck 10 equalizing arrangement.

One object of the invention is to provide a simple and efficient six-wheel equalizing truck arrangement whereby an equal division of the bolster end loads to the middle 15 journal boxes on both sides of the truck is insured and, accordingly, any tendency of said middle journal boxes to tilt is overcome.

Another object is to provide a simple co- 20 operative arrangement between the equalizing levers and middle journal boxes to meet the various requirements under service conditions.

These and other objects are accomplished 25 by means of the arrangement disclosed on the accompanying sheet of drawings, in which—

Figure 1 is a fragmentary vertical sectional view of a six-wheel truck embodying 30 my invention; and

Figure 2 is a sectional view taken in the plane of line 2—2 of Figure 1.

The various novel features of the invention will be apparent from the following 35 description and drawings, and will be particularly pointed out in the appended claims.

Referring to the figures of the drawings, it will be noted that I have disclosed my invention in connection with a six-wheel car truck 40 having a side frame 10 with depending walls 11 having a relatively large central opening 12 for the reception of an intermediate journal box 13 and also having openings, not shown, for the end journal boxes. The 45 side frame 10 also has openings 14 for the reception of transversely extending bolster members 15 which rest upon equalizing levers 16 whereby loads are transmitted through said equalizing levers to the various 50 journal boxes. The equalizing levers 16 preferably are located between the side walls 11 of the side frame and pivotally connected thereto by suitable fulcrum pins 17. The equalizing levers preferably extend longitudinally inwardly and bow downwardly to

form a seat for the bolster members 15 and then extend inwardly and upwardly and terminate in longitudinally extending overlapping portions 18. Roller members 19 are carried by the equalizing levers 16 and 60 engage the side walls of the middle journal box for guiding the latter in its vertical movements. Each equalizing lever has a bracket 20 which is adapted to receive a member 21 which in turn rests upon a spring 65 cap 22 resting upon a plurality of springs 23 and 24, which springs are mounted in pockets 25 at each side of the journal box and on opposite sides of the journal receiving portion 26 thereof. The pins 27 which 70 are carried by the equalizing levers and upon which the rollers 19 are directly mounted, lie substantially in the same horizontal plane with the equalizing lever fulcrum 17, so that as the equalizing levers 75 may rise and fall there will be no tendency to cramp the intermediate journal box or to prevent its free vertical movement. It will be noted also that the members 21 engage the spring caps 22 in practically the same 80 horizontal plane, so that any relative vertical movement between the side frame and the journal box will cause very little relative horizontal movement between the members 21 and spring caps 22. 85

It will be noted that the equalizing levers are duplicates, the inner reduced ends 18 which overlap each other resting upon a shelf 28 on the other or complementary equalizing lever. As shown, the lower surfaces of the inner ends of each of these equalizing levers is convexly curved, as also is each of the shelf portions 28 to permit a free rocking movement of the equalizing levers as they rise and fall in a vertical direction. 95

The inner end portions 18 of the equalizing levers which are opposite with respect to each other and overlap, rest upon the associated equalizing lever at points over the center of the springs 23 and 24, but such does not necessarily have to be the case. The overlapping arrangement neutralizes any difference in loads transmitted to the levers by the bolsters by reason of the contacts of 100 equalizing lever portions 18 with the shelf portions 28. For example, if there is an excess load on left hand lever 16, any tendency toward rotation or tilting of the journal box in a counter-clockwise direction, as 105 110

viewed in Figure 1, is checked or prevented by reason of the fact that the inner end of the portion 18 of left hand lever 16 bears upon the right lever shelf portion, thus dividing the difference in load.

By means of the arrangement disclosed there is insured practically an equal distribution of the bolster end loads on either side of the truck to the middle journal springs, thereby overcoming any tendency for the 10 middle journal box to tilt. Also, the equalizing levers have freedom of movement with respect to the side frames and with respect to the journal boxes and, at the same time 15 the intermediate journal boxes are guided in their vertical movements in a manner to meet all the requirements under service conditions.

It is my intention to cover all modifications of the invention falling within the 20 spirit and scope of the following claims.

I claim:

1. In a six-wheel truck, the combination 25 of a side frame, a journal box associated therewith, and equalizing levers having overlapping portions, one resting on the other at a point over said journal box for transmitting a load to said journal box and neutralizing any difference in loads transmitted to 30 said equalizing levers.
2. In a six-wheel truck, the combination 35 of a side frame, a journal box associated therewith, and duplicate equalizing levers having overlapping portions each resting on the other for transmitting a load to said journal box and neutralizing any difference in loads transmitted to said equalizing levers.

3. In a six-wheel truck, the combination of a side frame, a journal box associated therewith, and equalizing levers, each equalizing lever having a shelf portion and an extending portion, the extending portion of one equalizing lever resting upon the shelf portion of the other equalizing lever for transmitting a load to said journal box and neutralizing any difference in loads transmitted to said equalizing levers. 40

4. In a six-wheel truck, the combination 45 of a side frame, a journal box associated therewith, and equalizing levers having overlapping portions with one resting on the other and extending over said journal box for transmitting a load thereto and neutralizing any difference in loads transmitted to 50 said equalizing levers.

5. In a six-wheel truck, the combination 55 of a side frame, a journal box, springs carried by said journal box, and equalizing levers having overlapping portions, one resting on the other at points above said springs for neutralizing any difference in loads transmitted to said equalizing levers. 60

6. In a six-wheel truck, the combination 65 of a side frame, a journal box, equalizing levers having overlapping portions, one engaging the other, and resilient means interposed between said equalizing levers and said journal box whereby a load is transmitted from said equalizing levers to said journal 70 box.

Signed at Chicago, Illinois, this 15th day of May, 1922.

KATSURO ISHIBASHI.
